ROBERT B. SEWARD, OF GUILFORD, CONNECTICUT, ASSIGNOR TO ZOTOS CORPORATION, OF NEW YORK, N. Y., A CORPORATION OF NEW YORK

HAIR WAVING DEVICE

Application filed November 30, 1932. Serial No. 644,959.

This invention relates to certain improvements in hair waving devices in which a pre-formed tress of hair is subjected to the action of an exothermic material which, when moistened, will of itself generate heat sufficient to impart a so-called permanent wave to the tress.

My improved hair waving device comprises a capsule containing an exothermic material and a capsule containing a liquid reagent therefor, the capsule which contains the exothermic material being either soluble or puncturable, as desired, and the capsule which contains the liquid reagent being puncturable but not soluble, said capsules telescoping one within the other and being preferably of tubular form.

Practical embodiments of my invention are represented in the accompanying drawing, in which:

Fig. 1 represents in side elevation one form of my improved hair waving device in which the use of a mandrel for the wound tress is eliminated;

Fig. 2 represents a longitudinal central section through the same, the tubular capsule containing the liquid reagent being inserted between the capsule containing the exothermic material and the tress which is wound upon the capsule containing the liquid reagent;

Fig. 3 represents a similar view in which the positions of the two capsules are reversed, the hair tress being wound around the tubular capsule containing the exothermic material;

Fig. 4 represents in side elevation another form of my improved hair waving device in which the hair tress is wound upon a mandrel;

Fig. 5 represents a longitudinal central section through the same, the tubular capsule containing the exothermic material being inserted between the wound tress and the tubular capsule containing the liquid reagent for the exothermic material; and

Fig. 6 represents a similar view in which the positions of the two capsules are reversed.

The outer wrapper is denoted by 1, which

absorbent material, such as parchment paper, foil, or the like. The clamp is denoted by 2, which clamp may be of any well known or approved form. It is to be understood that any suitable protective pad, not shown herein, 55 may be inserted between the clamp 2 and the scalp of the person being treated.

The capsule 3 which contains the exothermic material 4, preferably in powdered form, is either soluble or puncturable, as desired. This capsule is preferably of tubular form. The capsule 5 which contains the liquid reagent 6 for the exothermic material 4 is preferably of tubular form and is made of readily puncturable material. 65

In Fig. 2, the hair tress 7 is shown as wound around the tubular capsule 5 which contains the liquid reagent and the tubular capsule 3 which contains the exothermic material is shown as inserted within the tubular 70 capsule 5, while in Fig. 3 the hair tress 7 is shown as wound around the tubular capsule 3 which contains the exothermic material and the tubular capsule 5 which contains the liquid reagent is shown as inserted within 75 the capsule 3.

In Figs. 4, 5 and 6 the hair tress 7 is shown as wound upon a mandrel 8 of any well known or approved form. In Fig. 5 the capsule 3 containing the exothermic material 80 is inserted between the wound tress and the capsule 5 containing the liquid reagent for the exothermic material. In Fig. 6 the capsule 5 containing the liquid reagent is inserted between the wound tress and the capsule 3 containing the exothermic material. 85

In practice, after the tress has been wound around the tubular capsule 5 containing the liquid reagent as shown in Fig. 2, or around the capsule 3 containing the exothermic material as shown in Fig. 3, or around the mandrel as shown in Figs. 5 and 6, the tubular capsule 5 may be punctured to release the liquid reagent and the capsule 3, in case it is of non-soluble material, is also punctured. 95 The outer wrapper 1 may be wrapped around the wound tress after the capsules are in position and secured at the scalp end by the clamp 2, the outer end of the wrapper being twisted together to close the same after the punctur- 100

ing of the capsule or capsules. In case the tubular capsule 3 is made of soluble material it will not have to be punctured.

The exothermic action starts at once, where 5 the capsule containing the exothermic material is punctured, because of the application of moisture to the exothermic material by the release of the liquid reagent in the punctured capsule 5. Where the capsule contain- 10 ing the exothermic material is soluble the liquid reagent first dissolves the capsule sufficiently to gain access to the exothermic material.

Heat is thus set up within the device suffi- 15 cient to impart a so-called permanent wave to the preformed tress without requiring application of heat from an outside source.

It will be seen that the outside wrapper serves to confine the heat to a large extent 20 within the device, the steam generated by the reaction of the liquid reagent with the exothermic material being permitted to escape through the crimped outer end of said wrapper.

25 It is evident that various changes may be resorted to in the construction, form and arrangement of the several parts without departing from the spirit and scope of my invention, and hence I do not intend to be 30 limited to the particular embodiments herein shown and described, but

What I claim is:

35 1. A hair waving device comprising a soluble capsule containing an exothermic material and a puncturable capsule containing a liquid reagent for the exothermic material.

40 2. A hair waving device comprising a puncturable capsule containing an exothermic material and a puncturable capsule containing a liquid reagent for the exothermic material.

45 3. A hair waving device comprising a soluble capsule containing an exothermic material and a puncturable tubular capsule containing a liquid reagent for the exothermic material.

50 4. A hair waving device comprising a puncturable capsule containing an exothermic material and a puncturable tubular capsule containing a liquid reagent for the exothermic material.

55 5. A hair waving device comprising a soluble tubular capsule containing an exothermic material and a puncturable capsule containing a liquid reagent for the exothermic material.

60 6. A hair waving device comprising a puncturable tubular capsule containing an exothermic material and a puncturable capsule containing a liquid reagent for the exothermic material.

65 7. A hair waving device comprising a soluble tubular capsule containing an exothermic material and a puncturable tubular

capsule containing a liquid reagent for the exothermic material.

8. A hair waving device comprising a puncturable tubular capsule containing an exothermic material and a puncturable tubular 70 capsule containing a liquid reagent for the exothermic material.

9. A hair waving device comprising a soluble tubular capsule containing an exothermic material and a puncturable tubular 75 capsule containing a liquid reagent for the exothermic material, the exothermic material containing capsule being inserted into the liquid reagent containing capsule.

10. A hair waving device comprising a 80 puncturable tubular capsule containing an exothermic material and a puncturable tubular capsule containing a liquid reagent for the exothermic material, the exothermic material containing capsule being inserted into 85 the liquid reagent containing capsule.

11. A hair waving device comprising a soluble tubular capsule containing an exothermic material and a puncturable tubular capsule containing a liquid reagent for the 90 exothermic material, the liquid reagent containing capsule being inserted into the exothermic material containing capsule.

12. A hair waving device comprising a puncturable tubular capsule containing an 95 exothermic material, and a puncturable tubular capsule containing a liquid reagent for the exothermic material, the liquid reagent containing capsule being inserted into the exothermic material containing capsule. 100

13. A hair waving device comprising a soluble tubular capsule containing an exothermic material, a puncturable tubular capsule containing a liquid reagent for the exothermic material, the exothermic material containing capsule being inserted into the liquid reagent containing capsule, and a mandrel on which the hair tress is to be wound, insertable into the exothermic material containing capsule. 105

14. A hair waving device comprising a puncturable tubular capsule containing an exothermic material, a puncturable tubular capsule containing a liquid reagent for the exothermic material, the exothermic material containing capsule being inserted into the liquid reagent containing capsule, and a mandrel on which the hair tress is to be wound, insertable into the exothermic material containing capsule. 110

15. A hair waving device comprising a soluble tubular capsule containing an exothermic material, a puncturable tubular capsule containing a liquid reagent for the exothermic material, the liquid reagent containing capsule being insertable into the exothermic material containing capsule, and a mandrel on which the hair tress is to be wound, insertable into the liquid reagent containing capsule. 115

16. A hair waving device comprising a puncturable tubular capsule containing an exothermic material, a puncturable tubular capsule containing a liquid reagent for the exothermic material, the liquid reagent containing capsule being insertable into the exothermic material containing capsule, and a mandrel on which the hair tress is to be wound, insertable into the liquid reagent containing capsule.

17. A hair waving device comprising a soluble tubular capsule containing an exothermic material, on which capsule a hair tress is to be wound and a puncturable tubular capsule containing a liquid reagent for the exothermic material and insertable into the exothermic material containing capsule.

18. A hair waving device comprising a puncturable tubular capsule containing an exothermic material, on which capsule a hair tress is to be wound and a puncturable tubular capsule containing a liquid reagent for the exothermic material and insertable into the exothermic material containing capsule.

19. A hair waving device comprising a puncturable tubular capsule containing a liquid reagent for an exothermic material, on which capsule the hair tress is to be wound and a soluble tubular capsule containing an exothermic material and being insertable into the liquid reagent containing capsule.

20. A hair waving device comprising a puncturable tubular capsule containing a liquid reagent for an exothermic material, on which capsule the hair tress is to be wound and a puncturable tubular capsule containing an exothermic material and being insertable into the liquid reagent containing capsule.

21. In testimony, that I claim the foregoing as my invention, I have signed my name this 29th day of November, 1932.

ROBERT B. SEWARD.
